(57) **CLAIM**

The ornamental design for a handle, as shown and described.

DESCRIPTION

FIG. 1 is a top perspective view of a handle in accordance with the new design;

FIG. 2 is a top plan view thereof;

FIG. 3 is a bottom plan view thereof;

FIG. 4 is a left side elevation view thereof;

FIG. 5 is a right side elevation view thereof;

FIG. 6 is a front elevation view thereof; and,

FIG. 7 is a rear elevation view thereof.

The broken lines immediately adjacent to the shaded areas in FIGS. 1, 6 and 7 represent the bounds of the claimed design, with the lines themselves and areas within them forming no part of the claimed design.

1 Claim, 5 Drawing Sheets
